UNITED STATES PATENT OFFICE

CHESTER W. CRUMRINE, OF ROCHESTER, NEW YORK, ASSIGNOR TO ELECTROMATIC TYPEWRITERS, INC., OF ROCHESTER, NEW YORK, A CORPORATION OF NEW YORK

MASTER PERFORATOR

Application filed January 29, 1930. Serial No. 424,238.

This invention relates to punching machines, and more particularly to that class of punching machines used for perforating paper or other sheets, for master control sheets 5 to be used in mechanical and electrically operated machines, such as typewriters.

The principal object of this invention is to produce a machine of this kind which is simple in construction, inexpensive to make, 10 and in which means is provided for catching the disks ejected by the punches and conveying them away from the operating point of the machine, so that they cannot get into the mechanism.

15 Another object of the invention is to produce a machine of this kind having a hollow die into which the cut disks are deposited, and means for conveying the disks to one end of the die where they are discharged.

20 A still further object of the invention is to provide a machine of this kind with a cylindrical die having a revoluble spiral brush for moving the disks or slugs cut from the sheet along the die to prevent them from getting 25 into the mechanism of the machine.

Another object of the invention is to provide a machine of this kind with a feed roll revoluble on an oscillatory shaft, and a pawl and ratchet mechanism on said shaft for driving 30 the spiral brush in one direction.

To these and other ends, the invention consists in the construction and arrangement of parts that will appear from the following description when read in conjunction with the 35 accompanying drawings, the novel features being pointed out in the claims following the specification.

In the drawings:

40 Figure 1 is an end elevation of a portion of a punching machine illustrating one embodiment of the invention;

Figure 2 is a transverse section through the die and illustrating the relation of the punch thereto, and

45 Figure 3 is a front elevation of the left hand end of the machine, partly in section on the line 3—3 of Figure 1.

50 Referring particularly to the drawings, in which similar reference numerals refer to the same parts in all figures, 1 indicates the frame

in which the shaft 2 is mounted for oscillating movement. A feed roll 3 is mounted on the shaft to rotate thereon and is provided with devices for rotating it one unit distance each time one of the punch keys is depressed, as 55 is usual in the art. Each end of the feed roll is provided with one or more circumferential rows of projections 4 which are adapted to engage similarly spaced openings in the margins of a work sheet 5. By this 60 arrangement, rotation of the feed roll moves the work sheet an equal distance.

Mounted in the frame and fixed therein adjacent the feed roller is a die 6, with which there cooperates means for conveying the 65 ejected disks away from the punching point, and to accomplish this, the die is preferably cylindrical as shown, although it may be otherwise constructed while affording a conveyor of some other form. The die, at its 70 front side, is provided with a plurality of openings 7 arranged in a substantially horizontal line for cooperation with the punches 8 presently to be described.

The work sheet is held between feeding operations against the die over the openings 7. It is guided to the die preferably by means of an apron 9 secured on the frame or a block 10 extending between and secured to the ends of the frame. The apron 9 extends forwardly beneath the die and is curved upwardly at the front of the die to direct the sheet over the openings 7 in the front wall thereof. As shown, the apron 9 is provided with offset ears 11 adapted to engage headed screws or 80 pins 12 projecting rearwardly from the block 10.

The block 10 extends transversely of the machine and is provided with a plurality of longitudinally arranged openings 15 each 90 aligned with one of the openings 7 in the die 6 and forming a guideway for a punch 8 slidably therein. The punch 8 is actuated by a lever or arm 16 pivoted in the frame at 17 and connected at its upper end with the rear end of the punch, the arm 16 being operated by suitable means not shown.

The arm 16 may be operated manually from a keyboard, or mechanically by means of power driven devices under the control of a 100

keyboard. It will be understood that when operated, the arm 16 slides the punch 8 rearwardly in its guideway into engagement with its corresponding opening in the die 6 and the work sheet thereon. Resilient means, such as a spring, may be employed for returning the lever 16 and the punch connected therewith to normal position, in which a stop 20 on an arm projecting rearwardly and upwardly from the arm 16 engages the block 10 and limits the action of the spring. The forward movement of the punch is limited by the engagement of the arm 16 with the block 10, which engagement takes place as soon as the punch has cut entirely through the sheet. By this action, the disk or slug cut from the sheet is ejected forwardly through the wall of the die in which it is deposited.

20 Means are provided for conveying the disks deposited in the die longitudinally thereof and discharging them through an opening 23 provided for the purpose at one end of the die. Said means may comprise a screw or 25 spiral device 24 arranged axially in the die, and means for rotating the same. The spiral device or screw is preferably constructed of resilient material and may be made in the form of a spiral brush as shown, which is connected to a stub shaft 25 revolubly mounted in a block 26 at one end of the die.

25 Means are provided for turning the shaft 25 and the spiral brush in one direction for conveying the disks along the die and discharging them therefrom. To this end, a pulley 27 is secured to the outer end of the shaft and connected by a flexible belt 29 to a pulley 28 revolubly mounted on the shaft 2. Secured to or formed integral with the pulley 28 is a toothed wheel 30 in the form of a ratchet, and cooperating with this wheel is a pawl 31. The pawl 31 is carried on an arm 32, to which it is pivoted, and a spring 33 is secured at one end to the arm and has its other end connected with the pawl for resiliently maintaining it in operative engagement with the teeth of the ratchet wheel. The arm 33 is secured to the shaft 2 and turns therewith. When the shaft is turned in one direction, the pawl rides idly over the teeth of the ratchet wheel, but when turned in the other direction, it engages the teeth, and the ratchet wheel and the pulley 28 secured thereto turn as a unit with the shaft. Rotation of the pulley 28 is transmitted to the pulley 27 through the belt 29, thus effecting rotation of the spiral brush to convey the disks along the die. If desired, a suitable receptacle for the disks may be arranged adjacent the opening 23 into which they could fall by gravity.

30 Although this invention has been described with reference to a single embodiment thereof, it will be understood that this application is intended to cover such changes or

modifications thereof as come within the spirit of the invention or scope of the following claims.

I claim:

1. In a sheet punching machine, the combination of a hollow die, a feed roller for moving a work sheet thereover, an oscillatory shaft on which said feed roller is revolubly mounted, a ratchet wheel revoluble on said shaft, a pawl on said shaft cooperating with said ratchet wheel for turning the same in one direction, a shaft in said die, a conveyor thereon, and means operatively connecting said second shaft with said ratchet wheel. 70
2. In a sheet punching machine, the combination of a hollow die, a feed roll for moving a work sheet thereover, an oscillatory shaft on which said feed roll is mounted, a ratchet wheel revoluble on said shaft, a pawl on said shaft cooperating with said ratchet wheel for turning the same in one direction, a shaft in said die, a conveyor thereon, and flexible means operatively connecting said second shaft with said ratchet wheel. 80

In witness whereof, I have hereunto signed my name.

CHESTER W. CRUMRINE.
